C. S. PRICE,
MAGNETO RECHARGER,
APPLICATION FILED DEC. 23, 1920.

1,408,532.

Patented Mar. 7, 1922.

UNITED STATES PATENT OFFICE.

CHARLES S. PRICE, OF KANSAS CITY, MISSOURI, ASSIGNEE TO THE WALBY STORAGE BATTERY AND PLATE MANUFACTURING COMPANY, OF KANSAS CITY, MISSOURI, A CORPORATION OF MISSOURI.

MAGNETO RECHARGER.

1,408,532.

Specification of Letters Patent.

Patented Mar. 7, 1922.

Application filed December 23, 1920. Serial No. 432,804.

To all whom it may concern:

Be it known that I, CHARLES S. PRICE, a citizen of the United States, residing at Kansas City, in the county of Jackson and 5 State of Missouri, have invented certain new and useful Improvements in Magneto Re-chargers; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to a magneto re-energizing device; that is, to means for re-energizing the permanent magnets of a magneto such as, for example, is used as part of the ignition system of the type of motor 20 vehicle now manufactured by the Ford Motor Company of Detroit, Michigan.

This type of magneto includes a plurality of permanent magnets, approximately sixteen, and under certain conditions during 25 use, the magnets become de-energized. Therefore, in order to restore the magneto to its efficiency, new permanent magnets must be substituted or the magnets must be re-energized to their original condition. 30 Heretofore various attempts have been made to accomplish the desired result with more or less success but the success depends to a great extent upon the skill of the operator.

I have provided a re-energizing or re-35 charging device which will efficiently recharge the permanent magnets in an expeditious manner, the device being adapted to be operated without any special knowledge on the part of the operator and the 40 construction is such that uniform, satisfactory results can be obtained.

In the drawings,

Fig. 1 is a perspective view of a device constructed in accordance with my invention, the magneto of conventional form being shown in side elevation and electrically connected to the device.

Fig. 2 is a wiring diagram of the device.

Fig. 3 is a sectional view through the 50 instrument board, showing the manner of connecting one of the binding posts, and

Fig. 4 is a wiring diagram of a conventional form of ignition system.

Referring now to the drawings by numerals of reference:

1. designates an instrument board which may consist of any suitable insulating material and which is supported upon a shelf 55 2 mounted upon the standards or legs 3 to superpose the board above the floor. The 60 essential operating mechanism is carried by the instrument board; the source of current supply may consist of a commercial line wire or any other source. In Fig. 2 the source of generation is indicated at 4, the symbol 65 designating a generator.

The conductors 5 and 6 lead to the switch 7 on the instrument board 1, the switch being provided with the usual contacts 8 and 9. The contact 9 is in electrical connection 70 with the rheostat 10, from which a conductor 11 leads to a swinging contact arm 12 insulated on the instrument board and having a movable electric contact 13 to swing in an arc over the circular series of contacts 75 14, electrically connected to the ring-shaped conductor 14', which, in turn is connected to a conductor 15, leading to the binding post 16 on the instrument board. The contacts each comprise a head on the end of a shank 80 17, which passes through the instrument board and is secured thereto by a collar 18, there being a binding nut 19 by means of which the conductor 14' may be fastened to the binding post, as will be well understood. 85 A conductor 21 is shown as connected to the binding post 16 and to a binding post 22 in circuit with the series of coils 23 of the magneto 24, the coils being grounded to the crank case so that the return circuit may be 90 connected at 25 through the conductor 26 to binding post 27, through conductor 28, ammeter 29, back to contact 8 and through the switch to conductor 6 to the generator.

Between the live contacts 14, that is, alternating therewith, are dead contacts 30 so that as the swinging contact 13 moves in the arc, said contact 13 will alternately pass over a live contact and a dead contact, causing an intermittent, uniformly spaced 100 interruption of the current; that is, there will be a uniform making and breaking of the current when the arm 12 is swung on its pivot at a uniform rate of speed whereby the coils 23 will become energized by current supplied from the generator 4.

In actual practice the instrument board will be set up as shown in Fig. 1, with the conductors 21 and 26 ready to be applied to the binding post 22 and the ground 25 respectively and the rheostat 10 will be adjusted for the proper amperage which may be indicated on the ammeter 29. Then the swinging contact or crank 12 will be rotated about the axis of its pivot over the alternating live and dead contacts 14 and 30 to cause a relatively rapid make and break of the circuit, resulting in an efficient recharging of the permanent magnets 31 of the magneto. As soon as the magneto has been properly charged, the connections 22 and 25 may be broken and the magneto will be ready to operate in the usual way.

The shelf 2 is adapted to carry a seat or rest consisting of the members 31 and 32 to receive a coil box 33, provided with contacts 34, 35 and 36 to rest against the contacts 37, 38 and 39 in circuit with the battery through the conductors 40, 41, and 42. Interposed in the conductor 41 are the contacts 44 and 45, which are adapted to receive a spark plug. The coil box having been placed in position with the spark plug receiving contacts 44 and 45, the vibrators of the coils can be inspected and in case of necessity, adjusted upon the shelf 2 at the same time that the permanent magnets 23

are electrically connected to the instrument board for recharging.

It will be apparent from the foregoing that whenever the permanent magnets of the magneto need recharging or re-energizing, it will be only necessary to connect up the connections 22 and 25 with the conductors 21 and 26, adjust the rheostat and swing the arm 12 about the contacts a sufficient number of revolutions to recharge or re-energize the magnets. Therefore, the magneto may be restored to operative condition in an expeditious and convenient manner.

What I claim and desire to secure by Letters-Patent is:

In a device for recharging the permanent magnets of a magneto, a conductor adapted to be connected to one of the line wires of a commercial circuit and to the binding post of the magneto whereby current will pass direct from the commercial line to the binding post, a conductor adapted to be connected to the other line of the commercial circuit and to a rotating contact, spaced contacts over which the rotating contact may pass, and a conductor connecting all of the spaced contacts to a ground on the magneto frame.

In testimony whereof I affix my signature.
CHARLES S. PRICE.
